AUXILIARY BEAM LETOFF MECHANISM
FOR LOOMSJohn A. Bradshaw, Greenville, S. C., assignor to
J. P. Stevens & Co., Inc., a corporation of Delaware

Application January 4, 1952, Serial No. 264,931

5 Claims. (Cl. 139—108)

1

This invention relates to letoff mechanisms for looms and more particularly to an improved mechanism of this sort for use in looms on which an auxiliary warp beam is employed for supplying supplementary warp ends in addition to the warp ends fed from a main beam to the loom.

In weaving fabrics such as seersucker cloth and the like, which are characterized by a puckered effect in the fabric, it is necessary to provide slack in certain of the warp ends in order to produce this puckered fabric texture. This is commonly done by feeding certain of the warp ends to the loom from a main warp beam in the usual manner and at the usual tension, and then providing an auxiliary warp beam from which supplementary warp yarns are fed separately to the loom at the necessary degree of slack. Usually the auxiliary warp beam is mounted above the main warp beam, and is therefore referred to as a "top beam," and the letoff mechanism of the present invention is uniquely adapted for unwinding the warp ends from a top beam of this sort at a regular rate for the degree of slack feeding desired or found necessary in any particular case.

The letoff mechanism of the present invention is described in detail below in connection with the accompanying drawings, in which:

Fig. 1 is a side elevation illustrating the manner in which a letoff mechanism constructed in accordance with the present invention is installed on a loom, the loom being represented only fragmentarily.

Fig. 2 is a fragmentary detail view related to Fig. 1 to show the manner in which the letoff mechanism of the present invention may be connected for actuation from a main operating element of the loom;

Fig. 3 is a fragmentary elevation taken from the rear of the loom as seen from the left in Fig. 1;

Fig. 4 is a further detail view related to Fig. 3 to show the other end of the letoff mechanism driving drum;

Fig. 5 is a sectional detail taken substantially on the line 5—5 in Fig. 3;

Fig. 6 is a further detail taken substantially on the line 6—6 in Fig. 3; and

Fig. 7 is a sectional detail taken substantially on the line 7—7 in Fig. 1.

Referring now in detail to the drawings, and more particularly at first to Fig. 1, the letoff mechanism of the present invention is shown as comprising a frame structure as indicated generally by the reference numeral 10, which is ar-

2

ranged for attachment to a conventional loom frame illustrated fragmentarily at F, and which may be provided with bracing arms 12 for further support from the loom arch indicated at A.

5 This frame structure 10 is adapted according to the present invention for carrying a driving drum 14, as will be explained more in detail presently, and is formed with guideways as at 16 for positioning an auxiliary warp beam B so that a warp end package P wound thereon will rest in peripheral driving contact on the driving drum 14. The guideways 16 are also preferably formed with a lip portion 18 at their upper ends to provide an elevated rest position for the warp beam 10 B free of the driving drum 14 to facilitate its handling upon installation and threading in the loom. The guideways 16 otherwise extend downwardly in the frame structure 10 with a reach sufficient to accommodate the full displacement 15 of the warp beam B while supported peripherally on the driving drum 14 as it moves from full position (as shown by full lines in Figs. 1 and 3) to the empty position indicated by dotted lines at B'.

20 It should also be noted that the guideways 16 are not arranged radially with respect to the driving drum 14, but are offset so as to be aligned more nearly in a tangent relation with the driving drum 14 at the side thereof that moves downwardly as the drum 14 rotates in order to obtain an increasing wedging effect between the rotating driving drum 14 and the opposing face of each guideway 16 as a warp end package P is unwound 25 from the warp beam B, and thereby compensate for the loss in weight of the unwinding warp beam B so that an effective driving contact is maintained with driving drum 14 until the warp beam B is completely exhausted. In particular cases, it may be desirable to provide very accurately for obtaining this increasing wedging effect 30 in relation to the weight loss of the beam B, and for this purpose the guideways 16 might be arranged with a calculated curvilinear form having the upper portion thereof at a more or less radial relation to reduce the wedging effect to a minimum at full position of the warp beam B and then curving downwardly to the above noted tangent relation in accordance with the rate at which the increase in wedging is calculated to be 35 necessary. However, in the usual case, an offset arrangement for the guideways 16 as illustrated in the drawings will provide satisfactory results.

The driving drum 14 is formed in a length less than the spacing between the end flanges of the 40 warp beam B, so as to operate in driving contact

only with the warp end package **P** wound between these end flanges, and is invested with a surface covering as at **20** formed of cork or other suitable material to provide it with a satisfactory surface driving action. Also, particularly where filament yarns are to be handled in the warp end package **P** carried by the warp beam **B**, there is considerable advantage in relieving this surface covering **20** in a pattern such as is provided by the spiral grooves **20'**, and by which the effective supporting portion of the surface covering **20** is continuously shifted laterally as the driving drum **14** is rotated. By this arrangement, the peripheral driving contact of the drum **14** with the package **P** is continuously shifted in relation to the individual ends of the package **P** so that an opportunity is afforded for distribution of any inequalities in tension between the individual ends such as must often be dealt with in handling filament yarns. The spiral grooves **20'** may start at each end of the driving drum **14** as illustrated in the drawings, so as to meet in a V-formation midway thereof, or the spiral may run continuously from one end of the drum **14** to the other, or any other comparable relieved pattern that will provide the laterally shifting support by the surface covering **20** as described above may be used as desired. The manner in which the driving drum **14** is carried on the frame structure **10** is illustrated best in Figs. 3 and 4, in which the driving drum **14** is shown journalled in housings **22** and **22'** that are supported on tie rods **24** and **26** forming part of the frame structure **10**, the tie rod **24** extending entirely across the frame structure **10** while the tie rods **26** extend only from each side to the adjacent housings **22** or **22'**.

Actuation of the letoff mechanism of the present invention is accomplished directly from a main operating element of the loom with which it is associated, and for this purpose the embodiment shown in the drawings is equipped with an actuating rod **28** (compare Figs. 1 and 2) fitted at one end with an eccentric collar **30** assembled on an eccentric **32** adapted to be fixed on the loom cam shaft **C** as illustrated in Fig. 2. At its other end, this actuating rod **28** is connected to the purchase arm **34** of a bell crank **36** for a pick mechanism **38**, the other arm **40** of which carries the shifting pawl **42** of the pick mechanism **38**. The purchase arm **34** is formed with an elongated slot **44** allowing the actuating rod **28** to be connected at varying distances from the axis of the bell crank **36** so that the pick mechanism **38** is rendered adjustable to vary the speed of rotation transmitted to the driving drum **14** as desired. The shifting pawl arm **40** of the bell crank **36** is also formed with an elongated slot **46** to allow the shifting pawl **42** to be positioned therein properly for smooth operation in relation to the ratchet or pick wheel **48** of the pick mechanism **38**. The ratchet **43** is fixed on a shaft **50** that also carries the bell crank **36** at its outer end, and that is journalled on the frame structure **10** in a bearing bracket **52** formed with an upstanding arm portion **54** adjacent the ratchet **48**, in which arm portion **54** an elongated slot **56** is provided for receiving and positioning a holding pawl **58** for the pick mechanism **38** (compare Figs. 3 and 7).

The inner end of the ratchet shaft **50** extends beyond the bearing bracket **52** to carry a pinion **60** disposed to engage a gear **62** on a countershaft **64** (compare Figs. 3 and 5). This countershaft **64** runs to the adjacent housing **22** in which the driving drum **14** is journalled, as already

mentioned above, and carries a pinion **66** engaging an intermediate gear **68** that is also journalled in this adjacent housing **22** to run in direct engagement with a drive gear **70** carried on the adjacent end of the mounting shaft **72** for the driving drum **14**. Through this geared arrangement, the driving drum **14** is rotated directly and regularly from the motion of the loom cam shaft **C**, or other operating element of the loom, for slack feeding of warp ends from the warp end package **P** on the warp beam **B** at a desired degree of slack as adjusted by the pick mechanism **42** in relation to the conventional feeding of warp ends from a main beam (not shown) to the loom.

In order to stabilize the geared drive for the winding drum **14** to operate smoothly as the let-off mechanism of the present invention is actuated through the pick mechanism **42**, the previously mentioned countershaft **64** which runs to the adjacent driving drum support housing **22** is fitted at its other end with a brake mechanism as at **74**. This brake mechanism (as shown best in Fig. 6) comprises a brake cylinder **76** on which are assembled a pair of pivoted clamping arms **78** and **80** both of which are fitted with brake shoes as at **82** and **84**. These clamping arms **78** and **80** extend from their common pivot joint at **86** to receive a pressure rod **88** at their extending ends. The extending end of the clamping arm **80** is formed to receive this pressure rod **88** through a retaining face as at **90** against which a compression spring **92**, disposed over the pressure rod **88**, is confined by a nut **94** engaging the extending threaded end of pressure rod **88**. The other clamping arm **78** is formed to provide a contact face as at **96** for a cam-like portion **98** of a manipulating lever **100** that is pivoted on the other extending end of the pressure rod **88** as at **102** for disposition at a retracted position against the adjacent clamping arm **78** to apply the brake mechanism **74**, or for pivoting outwardly from the adjacent clamping lever **78** towards a horizontal position so that its cam-like portion **98** releases the brake mechanism **74** when desired.

The present invention has been described above for purposes of illustration only and is not intended to be limited by this description or otherwise except as defined in the appended claims.

I claim:

1. An auxiliary beam letoff mechanism for slack feeding of supplementary warp ends in a loom, said letoff mechanism comprising an auxiliary frame structure adapted for attachment to a loom frame, a driving drum carried by said frame structure, guideways formed in said frame structure for positioning a warp beam to rest a warp yarn package wound thereon in peripheral driving contact on said driving drum, said guideways being arranged to extend from their remote ends in a path diverging from a radial direction with respect to said driving drum whereby the lateral reaction force from said driving drum against the opposing face of said guideways increases upon decrease in diameter of said warp yarn package and thereby compensates for loss in weight of said package on said driving drum during unwinding, and means for rotating said driving drum from the motion of a main operating element of said loom at a speed providing a degree of slack feeding of warp ends from said auxiliary beam as desired in relation to the warp ends fed from a main beam to said loom.

2. An auxiliary beam letoff mechanism for slack feeding of supplementary warp ends in a loom, said letoff mechanism comprising an auxiliary

frame structure adapted for attachment to a loom frame for positioning an auxiliary warp beam thereon, a driving drum carried by said frame structure and formed in a length less than the spacing between the end flanges on said auxiliary warp beam for supporting said auxiliary warp beam in peripheral driving contact with a warp yarn package wound thereon, means connecting said driving drum for rotation from the motion of a main operating element of said loom, and an adjustable pick mechanism interposed in said connecting means for varying the speed of rotation of said driving drum and thereby adjusting the slack feeding of warp ends from said auxiliary beam as desired in relation to the warp ends fed from a main beam to said loom.

3. An auxiliary beam letoff mechanism for slack feeding of supplementary warp ends in a loom, said letoff mechanism comprising a peripheral driving drum, means for mounting said driving drum in relation to the main frame of a loom and for supporting an auxiliary warp beam with a warp end package wound thereon resting on said driving drum, and means for rotating said driving drum from the motion of a main operating element of said loom at the desired speed of slack feeding of the supplementary warp ends from said auxiliary warp beam in relation to the warp ends fed from a main warp beam to said loom, said driving drum being formed with a peripheral surface that is relieved in a pattern by which the effective supporting portion of said surface is continuously shifted laterally as said driving drum is rotated.

4. An auxiliary beam letoff mechanism for slack feeding of supplementary warp yarns in a loom, said letoff mechanism comprising a peripheral driving drum, means for rotatably mounting said driving drum in relation to the main frame of

a loom and for supporting an auxiliary warp beam with a warp end package wound thereon resting on said driving drum, an adjustable pick mechanism geared to said driving drum, and means connecting said pick mechanism to follow continuously the motion of a main operating element of said loom for rotating said driving drum through said adjustable pick mechanism.

5. An auxiliary beam letoff mechanism for slack feeding of supplementary warp yarns in a loom having a camshaft for actuating the cyclic weaving operation thereof, said letoff mechanism comprising an auxiliary frame structure adapted for attachment to the frame of said loom for positioning an auxiliary warp beam thereon, a driving drum carried by said frame structure for supporting said auxiliary warp beam in peripheral driving contact with a warp yarn package wound thereon, an adjustable pick mechanism disposed on said frame structure and geared to said driving drum, and an actuating rod connecting said adjustable pick mechanism for operation continuously from said camshaft to rotate said driving drum at the rate desired for slack feeding of warp ends from said auxiliary beam in relation to the warp ends fed from a main beam to said loom.

JOHN A. BRADSHAW.
